ATTACHMENT FOR GOLF CLUBS

Joseph Belfore, Detroit, Mich., assignor to C. B.
Johnson, Detroit, Mich.Application October 20, 1934, Serial No. 749,249
Renewed February 18, 1937

2 Claims. (Cl. 273—81)

This invention relates to improvements in an attachment for golf clubs of the character to aid the player in making a proper and accurate stroke with the club, the invention being highly desirable for use in connection with golf clubs as a separate attachment to the club, or as an integral part of the club, although the invention may have other and various uses and purposes as will be apparent to one skilled in the art.

10 Although the present invention is described herein as being associated with a golf club of the type commonly known as a putter, it is to be understood that the invention may be associated in the same manner, if so desired, with other types 15 of golf clubs, or with such striking implements as croquet mallets, for example.

It has now become almost universally accepted that for best results in putting, almost entirely a wrist action should be used. It is well known 20 that a pendulum type of stroke would produce best results. I am aware that certain devices have heretofore been provided for cooperable association with a golf club in an endeavor to improve the player's stroke. However, with the ordinary golf club, especially that of the putter type, and with all of the aforesaid devices with which I was heretofore familiar, it is practically 25 an impossibility to consistently execute a stroke closely approximating a pendulum swing. With 30 the customary type of golf club, as well as with the devices heretofore known, an ordinary wrist action causes an opening of the face of the club during the stroke, thereby departing from a pendulum swing and necessitating a variant in order 35 to hit the ball in the proper direction. In order to acquire a proper pendulum swing, the first finger and thumb of the left hand (considering a right handed player) should not add any material pressure to the back stroke of the swing. 40 However, with the ordinary golf club and with devices heretofore known, the positioning of the first finger and thumb of the left hand has been such as to render it substantially impossible to prevent a back pressure and still keep the golf 45 club properly guided.

With the foregoing in mind, it is an object of the present invention to provide means associated with a golf club in such a manner as to permit a proper back swing to be made by pressure exerted by the last two or three fingers of the left hand, in the case of a right handed club, utilizing the index finger and thumb substantially as a point of suspension for the club.

At this point, it would perhaps be well to state 50 that the golf club shown and described herein is

a right handed club for a right handed player, and its operation is detailed for a right handed player. However, it will be obvious that in the event the club is made for a left handed player, the terms "left" and "right" herein can be reversed, and the description would give a true account of the construction and usage of a left handed club equipped with the present invention.

It is also an object of this invention to provide a device for association with a golf club to project from the handle of the club sufficiently to accommodate two or three fingers of the left hand, whereby the entire back swing can be accomplished by pressure from these fingers alone.

Still another object of this invention is the provision of a device for removable or permanent attachment to the handle of a golf club, the device being attached in such a manner and shaped in such a manner as to permit a ready and easy, substantially perfect pendulum swing of the club.

It is also an object of this invention to provide a device in connection with a golf club, the device projecting from the handle of the golf club in a direction opposite to the head of the club and arranged to counter-balance the club head.

Still a further object of this invention is the provision of a device in connection with a golf club, the device being arranged to accommodate the last two or three fingers of a hand of the player away from the shaft of the club, and the arrangement being further of such a nature that the first finger and thumb of the hand of the player may be used as a suspension or pivot for the shaft and the back swing executed by pressure from the last two or three fingers only.

It is also an object of this invention to provide a device either permanently or removably attached to a golf putter, the device being so shaped and arranged in disposition relatively to the putter so as to necessitate the use of only one hand of the player in executing a proper putting stroke.

While some of the more salient features, characteristics and advantages of the present invention have been above pointed out, others will become apparent from the following disclosures.

The invention includes these and other features of construction and combinations of parts hereinafter described, and shown in a preferred form in the drawing, as more particularly indicated by the claims.

On the drawing:

Figure 1 is a side elevational view of a golf club equipped with a device embodying principles of the present invention.

Figure 2 is an enlarged fragmentary view of the

top portion of the structure shown in Figure 1 together with a human hand, this view being in side elevation taken from the opposite side of Figure 1, to illustrate better the application of the fingers of the player.

Figure 3 is an enlarged plan sectional view through the device itself taken substantially as indicated by the staggered sectional line III—III of Figure 1.

Figure 4 is an enlarged side view, part in vertical section and part in elevation, the view being fragmentary and illustrating a modification in the joining of the device to the club handle.

Figure 5 is a fragmentary plan sectional view taken substantially as indicated by the line V—V of Figure 4.

As shown on the drawing:

As stated hereinabove, the present invention will be described in connection with a golf club of the type commonly known as a putter, but it will be obvious that the invention may be associated with any type of golf club, if so desired. For example, the invention might be associated with a mashie for short chip shots, with a cleek for approach shots, with a niblick, or with substantially any other club the player may desire.

In the illustrated embodiment of this invention, there is shown a golf club including a shaft 1, a putter head 2 at the lower end thereof, and a handle 3 on the upper end thereof. Associated with the upper end of the handle 3 is a gripping device generally indicated by reference numeral 4, embodying principles of the present invention.

The gripping device is preferably substantially of the shape of a pistol grip and preferably projects almost in its entirety away from the handle of the golf club, and is shaped to accommodate the last two or three fingers 5 of the player's hand 6 remote from the club handle, as best seen in Figure 2.

The device may be made of any desirable or suitable material, such as metal or a phenolic or alcoholic condensation product. In the case of a wooden shafted golf club, the device may also be of wood, if desired. The preferable form, however, is to cast the device from aluminum. If so desired, the weight of the device may be such as to counter-balance the weight of the head 2 of the golf club to a desirable extent, the device usually projecting from the handle of a golf club in a direction opposite to that of the club head 2.

One form of making the device is shown best in Figure 3. In this instance, the device is cast into two shells or half-portions, 7 and 8, respectively, the portion 7 preferably telescoping within the portion 8. Each of the shells 7 and 8 is provided with an arcuate portion 9 for embracing the handle 3 of the club, and each of the shells is also provided with internal bosses 10 and 11, respectively, which, when the shells are placed in cooperative position, confront each other. These confronting bosses are internally threaded to accommodate screws 12 and 13, respectively, by means of which the two halves of the device are held together rigidly embracing the handle of the club. Of course, the heads of the screws are preferably disposed in countersunk openings in the surface of the shell 7. When the device is assembled around the handle 3 of the shaft, the side walls 14 of the shell 8 preferably overlie the side walls 15 of the shell 7, so that the device is smooth and comfortable to the hand and pleasing in appearance.

The thickness and size of the device may be graduated as desired to best fit the hand of the

user and also to acquire the proper proportion of metal or weight of the device. If so desired, the club shaft may be shortened to a desirable extent, to provide the desired length of shaft after the attachment of the device, for any individual player.

In mounting the gripping member upon the handle of the club shaft, the shell 8 is first placed upon the handle with one of the side walls 14 of this shell overlying the upper end of the handle. The shell 7 can then be telescoped within the shell 8 and the screws 12 and 13 tightened into position clamping the two shells around the upper portion of the handle 3. If so desired, the screws 12 and 13 need only be loosened a sufficient extent, and the gripping member pushed downwardly over the top of the handle 3, the screws being tightened into position after the placing of the gripping member.

After so mounting the gripping member upon the club handle, it will be seen that the major portion of the gripping member projects rearwardly of the handle or shaft. Only that relatively small portion of the gripping member necessary to embrace the forward space of the handle or shaft, to hold the device rigidly in position, is disposed in projecting alignment with the club head.

The depth of the device is varied at intervals to provide finger notches 16, this variation in depth shaping the device to substantially that of a pistol grip. With such construction, as best seen in Figure 2, the last two or three fingers of the left hand (when the player is using a right handed club) may be accommodated on the gripping device away from the club handle. The first finger 17 and the thumb 18 of the player's left hand are disposed in substantially embracing position around the club handle, although the thumb may not exactly contact the handle of the club but may rest upon the front surface of the device. The rear face 19 of the device preferably rests substantially in the palm of the hand against the heel of the thumb. When so grasped, the back swing of the club may be made by pressure from the last two or three fingers 5 of the left hand only, this pressure being exerted with the aid of a slight wrist movement in a direction opposite to the line of flight. During the back swing, the forefinger 17 and thumb 18 are preferably held sufficiently loosely to merely function as a suspension or pivot for the club shaft and preferably exert no pressure to aid the back swing.

In this manner, the club head may be brought back in a substantially straight line in keeping with the line of flight, and the movement is steadied, resulting in a substantially perfect pendulum stroke of the club. The right hand, of course, may be disposed downwardly on the club shaft in advance of the left hand in position to be used in stroking the ball. The right hand preferably exerts no pressure, however, in the back swing of the club. It will be noted that with such an arrangement and in the manner above outlined, with a relatively short putt, the player need only hold the club in his left hand, make the back swing with pressure of the last two or three fingers of the left hand, release the pressure and permit gravity to execute the shot, utilizing the forefinger and thumb of the left hand as a suspension pivot for the action of the club.

In Figures 4 and 5, I have shown how the gripping device may be applied to a club shaft in order to be substantially integral with the

shaft rather than be selectively removable therefrom, as is the device described above. In this instance, I have shown a metal device attached to a metal shaft 20, the upper end of the shaft having had portions thereof cut away to provide longitudinally extending key-ways 21.

5 In mounting the device 22 on the shaft, the shaft is first finished and a plug 23 inserted in the upper end thereof to prevent an inflow of metal into the hollow of the shaft. The shaft is then utilized as a core and the gripping device is cast around the upper portion of the shaft, the metal flowing into the key-way 21 to anchor the gripping device securely to the shaft. The gripping member is of substantially the same shape and character as the one previously described, including the finger notches 16, with the exception that it cannot be removed from the upper end of the shaft.

10 20 The operation and use of the structure shown in Figures 4 and 5 is substantially the same as that previously described. It will also be understood that a wooden gripping member might be formed integrally with a wooden golf club shaft, if so desired.

15 From the foregoing, it will be apparent that I have provided a gripping device for association with the handle of a golf club, the device being in the form substantially of a pistol grip and aiding the player in making a substantially perfect pendulum swing of the golf club, permitting a back swing of the club as the result of pressure exerted by the last two or three fingers of the left hand only. It will also be readily understood 20 that the device is equally adaptable for use in connection with left handed golf clubs, it simply being necessary to mount the device in the opposite direction to a right handed club. In other words, it is preferable to have the device extend 25 away from the shaft in a direction opposite to the direction of the club head. Accordingly, if the device is used upon a left handed club, the gripping device is held in the player's right hand.

No change in construction of the device is necessary for it to be used with either a left handed or a right handed club.

It will also be noted that the device is simple in construction, yet very highly effective in use, 5 may be easily carried and handled, and may be economically manufactured.

I am aware that many changes may be made and numerous details of construction may be varied through a wide range without departing 10 from the principles of this invention and I, therefore, do not purpose limiting the patent granted hereon otherwise than necessitated by the prior art.

15 I claim as my invention:

1. As an article of manufacture, a gripping device attachable to the handle of an impact delivering member, said device including a pair of substantially complementary shells having interfitting parts to assure alignment, said shells being 20 shaped to accommodate the fingers of a user and having an opening therein closed at one end for receiving a portion of the handle of said member, and means for joining said shells over the handle portion, the closed ends of said openings serving 25 to limit the position of said article on a golf club when thereto applied.

2. As an article of manufacture, a gripping device attachable to the handle of a golf club, said device comprising two substantially complementary 30 parts having interfitting flanges to assure alignment and each part having a substantially semi-cylindrical portion closed at one end and adapted to fit about the end of the club handle, said closed ends of the semi-cylindrical portions abutting the 35 end of the handle and limiting position of said article on a golf club when thereto applied, removable means for securing said parts together about the handle, and said parts being shaped to provide a series of notches in stepped formation outwardly from the handle to accommodate the fingers of the user.

JOSEPH BELFORTE.
